COMBINED FLOOR FURNACE GUARD AND TABLE

William C. Sleeman, Birmingham, Ala.

Application December 31, 1954, Serial No. 33,777

Term of patent 7 years

(Cl. D81—1)

Fig. 1

Fig. 2

Fig. 3

Fig. 1 is a top plan view of a combined floor furnace guard and table showing my new design with the table top removed;

Fig. 2 is a side elevational view thereof;

Fig. 3 is an end elevational view thereof with the table top in place; and

Fig. 4 is an enlarged detail view of one of the support clips at the bottom. The table top surface not shown is plain.

I claim:

The ornamental design for a combined floor furnace guard and table, substantially as shown and described.
